Primary Examiner — Michael C Stout*Assistant Examiner* — Rani J Abdallah*(74) Attorney, Agent, or Firm* — Birchwood IP(57) **CLAIM**

The ornamental design for a folding wagon, as shown and described.

DESCRIPTION

FIG. 1 is a front, right and top perspective view of a folding wagon, showing our new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a view of the use state 1;

FIG. 10 is a view of the use state 2;

FIG. 11 is an enlarged view of portion of FIG. 1 thereof; and,

FIG. 12 is an enlarged view of portion of FIG. 1 thereof.

The dot-dash broken lines depict the boundaries of the enlargements that form no part of the claimed design.

1 Claim, 12 Drawing Sheets(56)
